UNITED STATES PATENT OFFICE.

JAMES L. MOORE, OF WELLSVILLE, NEW YORK, ASSIGNOR TO KERR TURBINE COMPANY, OF WELLSVILLE, NEW YORK, A CORPORATION OF NEW YORK.

STEAM-TURBINE.

No. 846,752.

Specification of Letters Patent. Patented March 12, 1907.

Application filed October 18, 1905. Serial No. 283,215.

To all whom it may concern:

Be it known that I, JAMES L. MOORE, a citizen of the United States, residing at Wellsville, in the county of Allegany and State of New York, have invented certain new and useful Improvements in Steam-Turbines, of which the following is a specification.

My invention relates to nozzles particularly adapted for compound steam-turbines, known more especially as the "multicellular type" and shown, for example, in the Patents No. 756,241, dated April 5, 1904, and No. 798,105, dated August 29, 1905.

The objects of my invention are, first, to construct a nozzle which consists of a series of nozzle-openings arranged on a ring, which is made separate and independent from the castings forming the turbine; second, to construct a nozzle-ring, as above indicated, whereby the nozzle-openings may be quickly and cheaply formed in the edge of the ring by a milling-cutter and at the same time made of a more durable material than cast-iron, such as bronze or other composition, thereby insuring greater strength and less corrosion; third, to construct a nozzle-ring in which the nozzle-openings may be placed closer together, so that in case of a partial admission of the motive fluid is admitted in a body and uniformly about the rotating element of the turbine; fourth, to construct a nozzle of greater power by cutting more nozzle-openings in a given diameter of nozzle-ring of a turbine; fifth, to construct a series of removable nozzle-rings of the same diameter and having different number of nozzle-openings, whereby the capacity of a turbine may be readily and widely changed by removing one set of nozzle-rings and inserting others having more or less nozzle-openings; sixth, to so construct and arrange the nozzle-openings with respect to the buckets that there is nearly a complete reversal in the direction of the motive fluid within the buckets while flowing in a general direction parallel to the axis; seventh, other evident advantages and features of the specific construction and arrangement of the parts, which will herein-after appear from the detailed description of the nozzle-ring and manner of constructing and applying the same.

My invention consists of structural features and relative arrangements of elements, which will be hereinafter more fully and

clearly described, and pointed out in the appended claims.

Referring to the two sheets of drawing, in which similar reference characters indicate the same parts in the several figures, Figure 1 is a central longitudinal section of two expansion-chambers, showing two of the nozzle-rings in position. Fig. 2 is a transverse section through the nozzle-opening on line 2 2 of Fig. 1. Fig. 3 is a transverse central section of the nozzle-ring removed from the turbine. Fig. 4 is a front elevation of one of the buckets removed from the bucket-wheel. Fig. 5 is a sectional view of a bucket, taken on line 5 5 of Fig. 4. Fig. 6 is a section of a bucket on line 6 6 of Fig. 5, and Fig. 7 is an enlarged sectional view showing a means of packing and making fluid-tight the joint between the nozzle-ring and the abutting walls separating one expansion-chamber from the next.

In the drawings the same reference characters indicate the same parts throughout the several figures.

Referring to the drawing, 1 1 represent the, bucket wheels or disks of the rotor element of the turbine, and 2 2 are the buckets on the periphery of the wheels.

3 is a rotary shaft passing centrally through the turbine-casing to which the wheels 1 1 are suitably secured.

4 4 are the separable sections of the turbine-casing which are fitted to each other and the ends of the cylinder by tongue-and-groove joints and held together by longitudinal bolts. (Not shown.) The outside portion of the casing may be provided with the usual lagging, as shown in the former patents hereinbefore referred to.

5 indicates one of the partitions separating one wheel or expansion chamber from the other and is preferably made integral and connected at one end of its corresponding casing-section 4 by means of any number of webs 5' 5', placed diametrically opposite to each other. The spaces between these webs 100 form extended arcuate-shaped passages for conveying the motive fluid from one section to the next succeeding section or stage of expansion.

6 is any suitable bushing or packing-gland 105 about the shaft and seated in the central shaft-opening of the partition 5.

7 is a cored casting which forms the end of

the cylinder and is provided with a motive-fluid chest 8, provided with any pipe connection 9, leading to a source of motive-fluid pressure.

5 10 is a bushing surrounding the shaft at the section where it passes through the end casting 7.

11 11 are internal annular depending flanges, made, preferably, integral with a turbine-section 4 4 and on the other end of the section from that of the partition or separating-wall 5 or on the same end of the section as the groove of the tongue-and-groove joint. The outer face of the flanges 11 11 are 15 made smooth and form with the rectangular passages in the nozzle-ring, to be presently described, the nozzle passages or openings for directing the motive fluid onto the moving buckets and in a given predetermined direction without leakage.

12 12 are the nozzle-rings, which are preferably made of bronze or other hard metallic composition, on which are provided by cutting on one of its flat sides or smooth faces a 25 series of rectangular-shaped passages 13 13, (see Fig. 2,) thereby forming the nozzle-openings of the nozzle-ring 12. The other face of the ring 12 is preferably provided with a circular tongue 14, which fits into an annular 30 groove 15 in the separating-wall or partition 5 on the end 7. (See Fig. 7.) In the groove 15 is deposited any suitable fibrous packing material 16 to make a tight joint with the tongue 14 to prevent any leakage of the 35 working fluid. This packing 16, it has been found, by its elastic qualities also assists in maintaining a fluid-tight joint between the opposite side of the nozzle-ring and the outer face of the flange 11, against which it rests. 40 It will be also seen that owing to the fluid-pressure back of the nozzle-ring being in excess of that on the opposite face, the immediate drop in pressure of the motive fluid when it enters the nozzles also exerts a pressure which is of assistance in maintaining 45 a fluid-tight joint on the nozzle side of the ring 12.

The single buckets 2, as shown in detail in Figs. 4-6, are provided with a shank 17, which 50 has at its lower end an enlargement 18 of cylindrical form, adapted to fit in a corresponding recess 19 in the periphery of the wheel 1. The curvature of the walls forming the inside of the bucket and the inclination of 55 the nozzle-passages are such that the motive fluid is reversed in direction, thereby efficiently imparting its velocity and energy to the rotor element of the turbine.

From the foregoing description of my invention it will be seen that the nozzle-rings can be easily manufactured of the same size of any suitable metal and with a different number of nozzle-passages, and when it is desired to vary the capacity of the turbine all 65 that is necessary to do is to remove the said

rings and quickly substitute others having the required number of passages without changing the construction or relation of the other parts of the turbine. Also, if so desired, the same turbine may have nozzle-rings with a different number of nozzle-passages in order to properly and uniformly distribute the torque in the different expansion-chambers or along the rotary shaft.

The operation of the invention is as follows: Referring to Fig. 1, the motive fluid passes 75 from the steam-chest 8 to the passage-ways 13 in the nozzle-ring, striking the buckets 2 on the wheel in such a direction that the velocity of the motive fluid is imparted to the 80 wheel, thereby rotating the shaft 3. The motive fluid in striking the buckets is turned back on itself in a direction almost opposite from that of the original or striking direction, whence it passes into a second chamber, 85 which acts as a motive-fluid chest for the succeeding stage of expansion. The motive fluid again passes through a series of similarly-arranged nozzle-passages until the last 90 stage of expansion to the final exhaust, as illustrated and described in the patents referred to above, and need not herein be further described for a clear understanding of the operation and use of the present invention.

95 From the foregoing description of the structural features, mode of assembling the different parts, and manner of operation it will be readily seen that I have devised a turbine in which all the objects recited in the 100 statement of invention are carried out, the parts of the turbine are easily and cheaply manufactured, its capacity readily changed, and the smooth and efficient running of a 105 turbine is easily effected.

110 Various changes may be made in the specific construction of the nozzle-ring and its mode of being supported and secured in the turbine, and while I have shown my preferred form I do not care to limit myself to these specific arrangements, as they could be modified in many ways without departing from the spirit of my invention and accomplish the same results.

Having now fully described my invention, 115 what I claim as new, and desire to secure by Letters Patent, is as follows:

1. A multicellular compound turbine comprising a cylinder composed of a series of separable and independent sections for the several stages of expansion of the motive fluid, a vertical partition or wall connected at one end of each of the sections and having peripheral openings for the passage of the motive fluid from one stage to the next succeeding 120 stage of expansion, a dependent flange extending from the inner side of the other end of each section from that of the partition on the same section, a rotary shaft passing centrally through each of said sections and par- 125 130

titions, a wheel or disk within each chamber formed by the separable sections and fixed to the shaft, a row of single buckets on the periphery of each wheel or disk and a removable nozzle-ring interposed between the outer end of each partition of one section and the dependent flange of the adjacent section.

2. A multicellular compound turbine comprising a cylinder composed of a series of separable and independent sections for the several stages of expansion of the motive fluid, a vertical partition or wall connected at one end of each of the sections and having peripheral openings for the passage of the motive fluid from one stage to the next succeeding stage of expansion, a circular groove in the outer face of the partition and near its outer edge, a short dependent flange extending from the inner side of the other end of each section from that of the partition on the same section, a rotary shaft passing centrally through each of said sections and partitions, a wheel or disk within each chamber formed by the separable sections and fixed to the shaft, a row of single buckets on the periphery of each wheel or disk and removable and independent nozzle-rings, each ring having a series of nozzle-passages in one of its flat faces and a circular tongue in its other face, said nozzle-rings being interposed and held between the dependent flanges and the partitions so that the nozzle-passages in each of the nozzle-rings are adjacent to the outer face of a dependent flange and the circular tongue rests within the groove of a partition.

3. A multicellular compound turbine comprising a cylinder composed of a series of separable and independent sections for the several stages of expansion of the motive fluid, a vertical partition or wall connected at one end of each of the sections and having peripheral openings for the passage of the motive fluid from one stage to the next succeeding stage of expansion, a circular groove in the outer face of the partition and near its outer edge, a short dependent flange extending from the inner side of the other end of each section from that of the partition on the same section, removable and independent nozzle-rings, each ring having a series of nozzle-passages in one of its flat faces and a circular tongue in its other face, said nozzle-rings being interposed and held between the dependent flanges and the partitions so that the nozzle-passages in each of the nozzle-rings are adjacent to the outer face of a dependent flange and the circular tongue rests within the groove of a partition, a rotary shaft passing centrally through each of said sections and partitions, a wheel or disk within each chamber formed by the separable sections and fixed to the shaft, a row of single buckets on the periphery of each wheel or disk, said wheels and buckets so arranged that the motive fluid passes into one side or edge of the buckets and escapes after reversal of its direction from the other side or edge of the buckets.

4. A multicellular compound turbine comprising a cylinder composed of a series of separable and independent sections for the several stages of expansion of the motive fluid, a vertical partition or wall connected at one end of each of the sections and having peripheral openings for the passage of the motive fluid from one stage to the next succeeding stage of expansion, a short dependent flange extending from the inner side of the other end of each section from that of the partition on the same section, removable and independent nozzle-rings, each ring having a series of nozzle-passages in one of its flat faces, said nozzle-rings being interposed and held between the dependent flanges and the partitions so that the nozzle-passages in each of the nozzle-rings are adjacent to the outer face of a dependent flange, a rotary shaft passing centrally through each of said sections and partitions, a wheel or disk within each chamber formed by the separable sections and fixed to the shaft, a row of single buckets on the periphery of each wheel or disk, said wheels and buckets so arranged that the motive fluid passes into one side or edge of the buckets and escapes after reversal of its direction from the other side or edge of the buckets.

5. A nozzle-ring for motive-fluid turbines or the like comprising an annular body having two opposite plane faces, a series of grooves or passages in one of said plane faces and a circular tongue or projection on the other face.

6. A separable section for a multicellular compound turbine, comprising an outer annular rim, a hub with central opening, a partition or diaphragm radiating from said hub and connected at its periphery by internal webs to one edge of the rim, a nozzle-ring removably supported on said partition or diaphragm thereby forming passages for the motive fluid from one section to another, and an internal flange at the other edge of the rim.

7. A multicellular compound turbine composed of a series of separable and independent sections, a rotary shaft passing through each of said sections, a wheel or disk fixed to said shaft within each chamber formed by adjacent sections, a series of buckets fixed to the rim of each disk, and a removable and continuous nozzle-ring held between adjacent sections in position to deliver the motive fluid tangentially to said series of buckets.

In testimony whereof I affix my signature in presence of two witnesses.

JAMES L. MOORE.
